B. C. ROCKWELL,

HINGE.

APPLICATION FILED SEPT. 10, 1918.

1,315,417.

Patented Sept. 9, 1919.

Inventor
Byrd C. Rockwell
By *J. M. General Atty.*

UNITED STATES PATENT OFFICE.

BYRD C. ROCKWELL, OF CAMDEN, ARKANSAS.

HINGE.

1,315,417.

Specification of Letters Patent. Patented Sept. 9, 1919.

Application filed September 10, 1918. Serial No. 253,397.

To all whom it may concern:

Be it known that I, BYRD C. ROCKWELL, a citizen of the United States residing at the city of Camden, county of Ouachita, 5 State of Arkansas, have invented a certain new and useful Improvement in Hinges, of which the following is a full, clear, and exact description, such as will enable others skilled in the art to which it appertains to 10 make and use the same, reference being had to the accompanying drawings, forming part of this specification.

My invention relates to hinges for supporting swinging structures, such as doors, 15 gates, windows, frames, panels, and the like, the principal object of my invention being to provide a relatively simple and efficient hinge, which can be easily and cheaply manufactured, and which is constructed so 20 as to permit the supported swinging structure to be readily removed from its supporting post or frame.

With the foregoing and other objects in view, my invention consists in certain novel 25 features of construction and arrangement of parts hereinafter more fully described and claimed and illustrated in the accompanying drawings, in which—

Figure 1 is a front elevational view of a 30 portion of a screen door or window, and a part of the frame to which said door or window is applied, and showing a hinge of my improved construction applied for use.

Fig. 2 is an elevational view looking in 35 the direction indicated by the arrow 2, Fig. 1.

Fig. 3 is a horizontal section taken approximately on the line 3—3 of Fig. 1.

Figs. 4, 5 and 6 are perspective views of 40 the three members forming my improved hinge.

Fig. 7 is a detail elevational view partly in section showing the members of my improved hinge in associated relation.

45 Referring by numerals to the accompanying drawings, 10 designates a post or upright member of a frame to which the swinging structure, such as a door, gate, or panel, is to be applied, and seated in said 50 post or frame is a short threaded rod 11, the same being horizontally disposed. The outer portion of this rod is bent substantially at right angles to the plane occupied by said rod to form a short vertically disposed pin- 55 tle 12, the upper end thereof terminating in a tapered or truncated conical bearing 13.

Seated in the edge of the door, gate, panel, or other swinging structure 14, is a short horizontally disposed rod 15, the outer end of which is bent to form a horizontally disposed loop or eye 16, the inner surface or periphery of which bears directly upon the tapered or conical bearing 13 at a point near the center thereof. Seated in the edge of the swinging structure 14, 60 immediately below the member 15, is a short rod 17, preferably threaded, the outer end thereof being bent to form a horizontally disposed loop or eye 18, the internal diameter or periphery of which is equal 65 to or slightly greater than the diameter of the pintle 12. When the members 15 and 17 are seated in structure 14, they are spaced apart so that when loop or eye 16 bears on the conical portion 13 of the 70 pintle, the loop 18 encircles said pintle and is positioned slightly above the point where the latter unites with the rod or shank 11. 75

By virtue of this construction, the eye or loop 16 engaging on conical bearing 13, 80 carries the weight of the swinging structure, and the loop or eye 18 engaging on the central portion of pintle 12, takes the greater portion of the lateral pull or stresses of the supported structure during its swinging 85 movement.

In the drawings, I have shown the rod or shank 15 as being formed without a thread and blunt at its inner end, and which construction will necessitate the forming of a 90 bore in the edge of the supported structure and the driving of said member 15 into said bore. Obviously, this shank 15 can be threaded and pointed the same as shanks or rods 11 and 17. 95

A hinge of my improved construction can be very cheaply produced, can be readily applied to the supporting post or frame and the supported structure, and can be advantageously employed in connection with 100 screen doors, storm doors, windows, gates, and panels, or any structure swinging upon a vertical axis.

A swinging structure supported upon hinges of my improved construction can be 105 easily and quickly removed from the supporting post or frame, and where the hinges are used upon screen doors, or the like, the members 15 and 17 are left in the door, thereby making it possible to easily and 110 quickly rehang the latter whenever desired.

It will be readily understood that minor

changes in the size, form and construction of the various parts of my improved hinge may be made and substituted for those herein shown and described, without departing 5 from the spirit of my invention, the scope of which is set forth in the appended claims.

I claim:

- 10 1. A hinge comprising a supporting member, the end portion of said member being bent into a plane substantially at right angles to the plane occupied by the body of said member to form a pintle, the same having bearing parts of different diameters, and a pair of separately formed members provided 15 with apertures of different diameters adapted to receive said pintle, said separately formed members being spaced apart when properly applied to the pintle and with the lower member occupying a position on said 20 pintle above and out of engagement with the body of the supporting member.
- 25 2. A hinge comprising a supporting member having a portion of one end bent into a plane substantially at right angles to the plane occupied by the body of said mem-

ber to form a pintle the end of which is tapered, and a pair of separately formed members provided with apertures, one of which is adapted to receive the body of the pintle, and the other adapted to receive the 30 tapered portion of said pintle, said members when properly applied to the supporting member being spaced apart with the lower one positioned slightly above the bend between the body portion of the supporting 35 member and the pintle thereon.

3. In a hinge, a supporting member comprising a shank, one end of which is bent to form a tapered pintle, and a pair of separately formed members, each of which comprises a shank one end of which is bent to form a pintle-receiving eye, one of which eyes is smaller than the other, said members when positioned on the supporting member being spaced apart with the lower 45 one engaging the pintle at a point above the shank of said supporting member.

In testimony whereof I hereunto affix my signature this 4 day of Sept., 1918.

BYRD C. ROCKWELL.
